VOLUNTARY TRUST.

INTERNAL-COMBUSTION ENGINE.

Application filed October 8, 1924. Serial No. 742,391.

Our invention relates generally to internal combustion engines of the two stroke cycle type, and more particularly to an engine power unit having three cylinders, the 5 head ends of two of which are connected by a common clearance space and function as combustion cylinders, and the third cylinder of the unit functioning as a pumping cylinder for forcing gaseous fuel charges 10 into the connected combustion cylinders.

The principal object of our invention is to provide an engine of the character referred to with a sleeve and means for reciprocating the same, which sleeve is arranged 15 within one of the combustion cylinders and functions to control the transfer of gaseous fuel charges from the pumping cylinder into the chambers of the combustion cylinders.

20 A further object of our invention is to provide simple and efficient means for driving the sleeve from the crank shaft of the engine and at the same speed therewith, and to arrange said driving connections so 25 that the sleeve is reciprocated in proper time relation to the movement of the pistons within the combustion chambers and the piston in the pumping cylinder.

With the foregoing and other objects in 30 view, our invention consists in certain novel features of construction and arrangement of parts that will be hereinafter more fully described and claimed and illustrated in the accompanying drawings, in which

35 Figure 1 is a transverse vertical section taken centrally through the three cylinders of an engine of our improved construction;

Figure 2 is a vertical section taken on the line 2—2 of Figure 1.

40 Referring by numerals to the accompanying drawings which illustrate a practical embodiment of our invention, 10 designates a cylinder block in which is formed a gaseous fuel pumping chamber 11 and a pair 45 of combustion chambers 12 and 13, the axes of all of said chambers being parallel with each other, and said axes intersecting the axis of the crank shaft 14 of the engine. This crank shaft is journaled for rotation in 50 suitable bearings 15 that are formed at the ends of a crank case 16, the latter being arranged beneath and connected to the cylinder block 10. The crank shaft 14 is pro-

vided with a crank 17 that is disposed in line with the pumping chamber 11 and said crank shaft is also provided with a crank 18 that is disposed in line with the combustion chambers 12 and 13. A piston 19 is arranged for reciprocatory movement within the pumping chamber 11, and said piston is connected to crank 17 by a connecting rod 20. Pistons 21 and 22 are arranged for reciprocatory movement respectively within combustion chambers 12 and 13, and said pistons are connected by suitable connecting rods, such as 23, to crank 18.

Secured to the central portion of crank 18 and between the bearings thereon that receive the connecting rods 23 is a counter-balancing member 24 that is designed to 70 counterbalance the weight of the connecting rods 23 and pistons 21 and 22 so as to minimize vibration of the crank shaft during engine operation. Formed through the wall of the pumping cylinder and at a point 75 where they are fully uncovered and opened only while pumping piston 19 is passing low or outer center are gaseous fuel inlet ports 25 that may be connected to a suitable source of gaseous fuel supply, for instance, a carburetor. Formed through the upper or inner portion of the wall between chamber 11 and the pumping cylinder and the combustion chamber 12 is a gaseous fuel transfer 80 port 26. These transfer ports communicate with an annular chamber 27 that surrounds the upper portion of combustion chamber 12, and leading from this annular chamber 85 through the inner portion of the wall into said chamber 12 are ports 28.

Formed through the wall of the block 90 that surrounds combustion chamber 13 is an exhaust port 29, the same being located so that it is uncovered and open only while piston 23 is passing low or outer center. Arranged for reciprocatory movement within the combustion chamber 12 and surrounding piston 21 therein is a sleeve 30 which, by its reciprocating movement, alternately covers and uncovers the inlet ports 28 that admit 95 the gaseous fuel charge from the pumping cylinder to combustion chamber 12. This sleeve is reciprocated in any suitable manner 100 in proper time relation to the movements of the pistons 19, 21 and 22, but we prefer to reciprocate said sleeve by the means illus-

trated in Figure 2, and which includes a link connection, such as 31, to a crank or cam on an eccentric shaft 32 that is driven directly from and at the same speed with 5 crank shaft 14.

Secured on top of the cylinder block 10 is a head block 33 in the under side of which is formed a pocket or recess 34 that coincides with and constitutes a clearance 10 space at the upper or inner end of pumping cylinder chamber 11. Formed in the under side of the central portion of head block 33 is a shallow chamber 35 that constitutes an 15 extension or clearance chamber for the head or inner end of combustion chamber 12, and leading from the side of this clearance chamber 35 to the immediately adjacent side of combustion chamber 13 is a shallow lateral extension or throat 36, the bottom of 20 which is inclined. The chamber 35 and lateral extension 36 constitute a common clearance space for the head or inner ends of the combustion chambers 12 and 13, and seated in head 33 above combustion chamber 12 is 25 an ignition device such as a spark plug 37, the inner ends of the electrodes of which project into clearance chamber 35.

In the operation of our improved engine the various operating parts occupy the positions as illustrated in Figures 1 and 2 at the time a compressed charge of gaseous fuel is ignited in the common clearance space above pistons 21 and 22, and the compressed charge is ignited as the result of a spark 30 produced between the terminals of the electrodes or plug 37. At this period in the cycle of operations crank 17 has moved a sufficient distance past low center to move pumping piston 19 into position to nearly 35 close the gaseous fuel inlet ports 25, it being understood that while said pumping piston was passing low center said inlet ports 25 were fully opened, thereby admitting to the pumping chamber 11 a charge of gaseous 40 fuel.

The rise in pressure following combustion of the ignited gaseous fuel charge in the clearance space comprising chamber 35 and throat 36 will be directed against the heads 50 of pistons 21 and 22 to move the same downwardly on their power stroke and as said pistons thus move downward or outward pumping piston 19 moves upward or inward, thereby compressing the gaseous fuel charge 55 within chamber 11 in the upper portion of said chamber and within clearance space 34. Simultaneously with the downward movement of the pistons 21 and 22 sleeve 30 will be drawn downward through connections 60 with the cam shaft that operates at crank shaft speed, but owing to the size and arrangement of the cam or crank to which said sleeve is connected its movement will be relatively slow, as compared to the movement of said pistons 21 and 22. As pistons

21 and 22 approach the lower ends of their travel piston 22 will uncover exhaust port 29 and immediately thereafter sleeve 30 will have moved downward to a position where transfer inlet ports 28 are uncovered, thereby admitting from pumping chamber 26 to the upper portion of chamber 12 a compressed charge of gaseous fuel, it being understood that at this time pumping piston 19 is at the upper or inner end of its stroke. 70 As the transfer ports 28 are thus opened simultaneously with the opening of the exhaust port 29 the inrush of gaseous fuel into the upper portion of chamber 12 drives before it through clearance chamber 35, 75 throat 36 and chamber 29 the burnt gases and products of combustion resultant from the previously ignited charge, and these products of combustion will be expelled through exhaust port 29, thus leaving within 80 the piston clearance spaces in the upper portions of chambers 12 and 13 and in clearance space 35 and throat 36 a charge of fresh gaseous fuel and a relatively small volume of residual products of combustion. 85 Sleeve 30 moves simultaneously with pistons 21 and 22, but at slower speed, owing to its relatively short overall travel; consequently 90 on the first portion of the upward or compression stroke of pistons 21 and 22 exhaust port 29 will be closed and simultaneously transfer inlet ports 28 will be closed by the sleeve, and on the succeeding upward travel 95 of pistons 21 and 22 the volume of gaseous fuel and residual products of combustion 100 within the combustion chambers will be compressed therein and within clearance chamber comprising the space 35 and throat 36. During this compression stroke of the combustion pistons, pumping piston 19 is 105 moving downward and on passing low center 110 it uncovers and opens inlet port 25 to admit to the pumping chamber 11 a fresh charge of gaseous fuel. As pistons 21 and 22 pass high center, or an instant later, a spark is produced between the terminals of the electrode or plug 37, thereby igniting the compressed gaseous fuel charge and, as hereinbefore described, the pistons 21 and 22 will 115 be forced downward on their power stroke. 118 Thus it will be seen that we have provided a relatively simple and practical power unit comprising a pair of connected combustion cylinders and a pumping cylinder and the transfer or inlet of gaseous fuel from the 120 cylinder into the adjacent one of the combustion cylinders being controlled by a sleeve that operates between the cylinder wall and the piston therein, said sleeve being connected so that it operates in proper 125 time relation to the movements of the pistons within the combustion and pumping cylinders.

Obviously, minor changes in the size, form and construction of the various parts of our 130

improved internal combustion engine may be made and substituted for those herein shown and described without departing from the spirit of our invention, the scope of which is defined in the appended claims.

We claim as our invention:

1. In a two stroke cycle internal combustion engine, a power unit comprising a pumping cylinder and a pair of combustion cylinders, the head ends of the latter being connected by a common clearance chamber, the pumping chamber being provided with a gaseous fuel inlet port, a gaseous fuel transfer port leading from the chamber in the pumping cylinder into the chamber of the adjacent combustion cylinder, the other combustion cylinder having an exhaust port, pistons arranged for operation within all of the cylinders, and a sleeve arranged for operation within the combustion cylinder having the gaseous fuel transfer ports for controlling the passage of gaseous fuel therethrough.
2. In a two stroke cycle internal combustion engine, a power unit comprising a pumping cylinder and a pair of combustion cylinders, the head ends of the latter being connected by a common clearance chamber, the pumping chamber being provided with a gaseous fuel inlet port, a gaseous fuel transfer port leading from the chamber in the pumping cylinder into the chamber of the adjacent combustion cylinder, the other combustion cylinder having an exhaust port, pistons arranged for operation within all of the cylinders, a sleeve arranged for operation within the combustion cylinder having the gaseous fuel transfer ports for controlling the passage of gaseous fuel therethrough,
3. and means for reciprocating said sleeves so that the same is at the top center to close said transfer ports while the pistons within the

combustion cylinders are at the upper or inner ends of their stroke.

3. In a two stroke cycle internal combustion engine, a power unit comprising a pumping cylinder and a pair of combustion cylinders, the head ends of the chambers within said combustion cylinders being connected by a common clearance space, one of the combustion cylinders being provided with an exhaust port, the other combustion cylinder being provided with gaseous fuel transfer ports that lead from the chamber within the pumping cylinder, and a sleeve arranged for operation within the combustion cylinder having the transfer ports for controlling the passage of gaseous fuel therethrough.

4. In a two stroke cycle internal combustion engine, a power unit comprising a pumping cylinder and a pair of combustion cylinders, the head ends of the chambers within said combustion cylinders being connected by a common clearance space, one of the combustion cylinders being provided with an exhaust port, the other combustion cylinder being provided with gaseous fuel transfer ports that lead from the chamber within the pumping cylinder, a sleeve arranged for operation within the combustion cylinder having the transfer ports for controlling the passage of gaseous fuel therethrough, pistons arranged for operation within all of said cylinders, a crank shaft to which said pistons are connected, and means for reciprocating said sleeve simultaneously with the pistons in said combustion cylinders.

In testimony whereof we affix our signatures.
